VACUUM CLEANER

Ivar Jepson and Julius P. Wied, Oak Park, Ill., assignors to Sunbeam Corporation, Chicago, Ill., a corporation of Illinois

Filed June 30, 1960, Ser. No. 39,865
14 Claims. (Cl. 15—323)

The present invention relates to suction or vacuum cleaners for removing dirt from floors, carpets, furniture and the like by virtue of the suction or vacuum produced by a motor driven fan.

So-called suction or vacuum cleaners particularly useful for use in the home have comprised two general types. One of these types commonly referred to as the upright cleaner comprises a housing having mounted therein a motor driven fan and also a rotatable brush driven by the motor. The housing terminates in a suction nozzle. Such a cleaner further includes a bag for receiving the dirt removed during the vacuum cleaning operation. The other type of cleaner commonly referred to as a tank or canister type cleaner gets its name from its construction. It commonly comprises a tank or similarly shaped unit containing a motor driven fan for producing a suction, and connected to this unit through a flexible hose are the various cleaning attachments. The present invention is directed to this latter type of cleaner, namely, the tank or canister type, which in recent years has gradually come to replace the so-called upright type cleaner.

The modern housewife's requirements for a vacuum cleaner are relatively stringent. First of all, she demands that such cleaner is capable of producing sufficient suction adequately to remove dirt lodged deeply in rugs or carpets. Furthermore, with the advent of the turbine driven brush, it must have adequate power to drive such brush without impairing the suction for removing the dirt. Another feature demanded by the modern housewife of a suction cleaner is that it be compact, light in weight, and easy to handle both during the cleaning operation and when moved to a place of storage. The housewife further demands that such a cleaner be designed so that dirt disposal is a clean, simple and easy chore. Also, it is important that the dirt be collected in a disposable bag, and that the removal of such bag and the insertion of a new bag be accomplished in a very simple and foolproof manner. Furthermore, such disposable bag should have a very large surface area to produce increased cleaner efficiency and increased economy. Still another feature demanded in a suction cleaner by the modern housewife is ease of control. A suction cleaner is started and stopped many times during a cleaning operation, and this should be accomplished in a simple manner whether the cleaner is standing in a so-called storage position or whether it is in the position normally employed during a cleaning operation. Still another feature demanded by the housewife is a simple manner of storing the necessary power cord which all vacuum cleaners require. Although not recognized so much by the housewife as an important feature is the fact that a permanent filter should be provided to preclude dirt from reaching the motor driven fan in the event that the disposable paper bag should be omitted, be improperly applied, or should develop a leak for some reason or another.

Accordingly, it is an object of the present invention to provide a new and improved tank or canister type cleaner that produces more power from the standpoint of cleaning suction than vacuum cleaners heretofore available and which is simple and compact.

It is another object of the present invention to provide a suction cleaner having the desirable features enumerated above.

It is another object of the present invention to provide a

2

new and improved vacuum cleaner which is sturdy in construction and which provides increased cleaning efficiency with maximum economy.

Still another object of the present invention resides in an improved vacuum cleaner having a wheeled housing wherein the wheels are recessed in the sides of the housing to the extent that the sealing gasket for closing the housing serves not only as a gasket but also as a bumper.

It is another object of the present invention to provide an improved vacuum cleaner having a mechanical arrangement of elements therein to provide a flat panlike design with means to open the entire top of the flat panlike construction to afford access to the interior of the housing for ready replacement and removal of a cleaning bag disposed in the same plane as the vacuum cleaner motor.

Still another object of the present invention is to provide an improved tank or canister type vacuum cleaner in which the housing is mounted on a pair of wheels in a substantially balanced manner so that the cleaner may readily be pivoted about the wheels.

Still another object of the present invention is to provide a new and improved vacuum cleaner employing a single stage fan of such large diameter as to provide much more suction than prior multistage fans.

It is a further object of the present invention to provide an improved vacuum cleaner with improved motor means.

Still another object of the present invention resides in an improved switch arrangement disposed on the underside of the housing which, however, can be operated by foot pressure from the top of the housing and yet which will not be inadvertently actuated as the cleaner is moved across the floor.

Another object of the present invention resides in an improved vacuum cleaner having a hinged air deflector or baffle at the point of air discharge from the vacuum cleaner housing.

Still another object of the present invention resides in improved mounting means for the motor driven fan together with improved filter and diffuser means therefor.

Still another object of the present invention resides in an improved vacuum cleaner with carrying means for carrying the cleaner from place to place designed for maximum comfort, together with simple means for supporting the vacuum cleaner in storage and storing the cord in a simple and yet readily accessible manner.

Further objects and advantages of the present invention will become apparent as the following description proceeds and the features of novelty which characterize the invention will be pointed out with particularity in the claims annexed to and forming a part of this specification.

For a better understanding of the present invention, reference may be had to the accompanying drawings in which:

FIG. 1 is a perspective view of the vacuum cleaner of the present invention showing a portion of the hose and wand and one of several cleaning attachments;

FIG. 2 is a side elevational view of the vacuum cleaner of the present invention without the hose or attachments, illustrating how the cleaner motor may be controlled by foot operation;

FIG. 3 is a top plan view of the cleaner of FIG. 2;

FIG. 4 is a side elevational view of the vacuum cleaner of the present invention with the hose and attachments removed, shown in the position which it assumes when stored, and further illustrating how the cord is supported for storage purposes;

FIG. 5 is an enlarged sectional view taken on line 5—5 of FIG. 3, showing the hose connected to the air inlet and with the cover shown in two positions thereof;

FIG. 6 is a sectional view taken on line 6—6 of FIG. 5, assuming that FIG. 5 shows the complete structure;

FIG. 7 is a sectional view taken on line 7—7 of FIG. 5, again assuming that FIG. 5 shows the complete structure;

FIG. 8 is an enlarged fragmentary sectional view taken on line 8—8 of FIG. 7, assuming that FIG. 7 shows the complete structure;

FIG. 9 is an enlarged fragmentary sectional view taken on line 9—9 of FIG. 7, again assuming that FIG. 7 shows the complete structure;

FIG. 10 is an enlarged fragmentary sectional view taken on line 10—10 of FIG. 7;

FIG. 11 is an enlarged fragmentary sectional view taken on line 11—11 of FIG. 10, assuming that FIG. 10 shows the complete structure;

FIG. 12 is a greatly enlarged sectional view taken on line 12—12 of FIG. 11;

FIG. 13 is a view partly in section of the hose assembly including the suction control portion of the vacuum cleaner of the present invention;

FIG. 14 is an enlarged sectional view of the hose hanger employed with the vacuum cleaner of the present invention taken on line 14—14 of FIG. 13;

FIG. 15 is a developed view of the hose hanger when disassembled from the hose;

FIG. 16 is a fragmentary bottom view with certain portions broken away of the specific rug cleaning attachment shown in FIG. 1 of the drawings; and

FIG. 17 is a greatly enlarged sectional view taken on line 17—17 of FIG. 1.

Briefly, the present invention is concerned with a tank type vacuum cleaner comprising a low compact housing of the shape of a shallow pan with a top cover having a circumference of the maximum diameter of the pan and gasket means between the cover and the remainder of the container which also defines a peripheral bumper for the cleaner. The cleaner is supported on suitable wheels which are recessed so as to be mounted inside the combined bumper and gasket. A powerful motor driven fan is mounted centrally of and within the pan-shaped housing so as to define an annular space for the reception of a disposable dust collecting bag of large surface area and volume. An improved single stage fan and diffuser insures the provision of a tremendous suction capable of sustaining a column of water seventy inches in height. Improved motor mounting means and diffuser and muffler means for reducing air noise and vibrations are provided. An improved motor controlling switch means is mounted on the underside of the cleaner housing with means, however, to operate this switch means from the top of the housing while eliminating inadvertent operation thereof.

Referring now to the drawings, there is illustrated a vacuum or suction cleaner generally designed by the reference numeral 30, which comprises a suitable housing comprising a pan-shaped member 31 and a cover 32 mounted on suitable wheels 33. The housing 31 is provided with means for connecting thereto a suitable tube coupling 35 secured to one end of a flexible suction hose 36. This hose is preferably formed from a nylon reinforced vinyl plastic, thus providing a light but long wearing construction. Preferably, the hose 36 at the end thereof remote from the tube coupling 35 includes a swivel 37 (FIG. 13) and a curved tube 38 removably connected with one end of one or more wand sections generally designated at 39. The curved tube 38 is provided with an adjustable suction control member 40 described in greater detail hereinafter. To the other end of the wand section may be secured various attachments such as the rug cleaning attachment generally designated by the reference numeral 41 in FIG. 1 of the drawings or suitable other attachments (not shown) such as an upholstery tool, a crevice tool, a dust brush, or a turbine brush such as is disclosed in and claimed in copending application of Jepson, Ernstberger and Wolter, Serial No. 42,080, filed July 11, 1960, now Patent No. 3,071,799 and assigned to the same assignee as the present application.

Considering now the base shell or panlike member 31 which forms a major portion of the housing of vacuum

cleaner 30, it comprises a panlike open top member of generally circular configuration having a rolled rim 31a surrounding the open top (FIGS. 5, 7, 8 and 9). On diametrically opposed positions of the circular side wall 31b of the pan 31 are provided an inlet opening 44 (FIG. 9) and an outlet opening 45 (FIG. 8). The base shell 31 is provided with a relatively flat annular bottom 31c between the vertical cylindrical wall 31b and a raised annular shelf portion 31d having an enlarged central opening 46 (FIGS. 6, 7 and 10) for receiving and supporting a motor driven fan unit to be described hereinafter. The raised central annular shelf 31d is provided with a plurality of notches 48 and 49, the notches 48 being semicircular and the notch 49 being rectangular, the purpose of which will become apparent from the ensuing description. For strengthening the annular bottom 31c, a plurality of raised ribs 31e integrally formed with the bottom and radially disposed as best shown in FIG. 7 of the drawings are provided. For aesthetic purposes, arcuate depressions 50, 51 and 52 are provided in the annular bottom 31c at the junction with vertical wall 31b, and the ribs 31e all terminate in these depressions. The end of the rib 31e, where it terminates in depression 50 adjacent the inlet opening 44, provides a sort of stop, the purpose of which will become apparent from the ensuing description. Preferably, this stop is formed by a slight enlargement of the end of this rib.

In accordance with the present invention, the side wall 31b of base shell or pan 31 is inwardly recessed on diametrically opposed sides as indicated at 53 and 54 to accommodate the wheels 33. The recesses 53 and 54 are identical and each effectively provides a flat wall section 31f (FIG. 7) to which is preferably welded a bracket 56 having a laterally projecting stud 57 extending away from the wall section 31f. A suitable nylon sleeve 58 mounted on the stud 57 provides a relatively frictionless bearing for the wheels 33. Preferably, a vinyl or plastic member 59, as best shown in FIG. 7, effectively provides a tire for the wheels 33. The wheels may be held on the stud 57 by any suitable member such as C-washer 60 receivable in an appropriate groove defined in the stud 57. To improve the appearance, a suitable closure plate or cup 61 may be provided for the center of each wheel, thereby hiding the stud and C-washer. In an embodiment built in accordance with the present invention, the base shell 31 was a metal stamping having a diameter of between fourteen and fifteen inches and a depth of the order of four inches. Moreover, the wheels 33 were made of a molded plastic, and the cup-shaped members 61 were suitably decorated metal members with integral clips extending through openings (not shown) in the wheels 33 to hold the members in position.

The annular bottom 31c of the base shell or pan 31 is provided with another opening 62 (FIG. 8) which is interconnected with the opening 45 by an exhaust elbow 64 generally designated at 64 and preferably formed of a rubber material. The exhaust elbow is provided at one end with an annular groove 65 to receive therein a portion of circular side wall 31b defining the opening 45, and similarly at the other end with a groove 66 to receive therein a portion of the annular bottom 31c defining the opening 62. To insure against the leakage of any air at the openings 45 and 62 where joined with the exhaust elbow 64, there are provided a pair of springlike expansion springs or rings 67 and 68 which are disposed in annular recesses 69 and 70, respectively. These springs or rings 67 and 68 are made of springlike material and maintain the circular configuration of the exhaust elbow, which is made of relatively flexible material.

In order that the vacuum cleaner may be supported in the manner shown in FIG. 4 of the drawings, which is characterized as the storage position, there is provided a base stand 74, preferably formed of a molded plastic, which base stand also defines a housing for a switch which is described hereinafter. As illustrated, the base stand

74 includes an upper arcuate portion 74a generally conforming to the circular configuration of pan wall 31b, and including an opening 73 therein aligned with the opening 45 and the exhaust end of elbow 64. This arcuate portion is provided with a plurality of pairs of projecting posts 74b and 74c which extend against the exterior of wall 31b of the base shell 31 and are secured thereto by suitable fastening means 75, best shown in FIG. 5 of the drawings. The lower portion of the base stand 74 includes a rearwardly directed angular extension 74d having a flat bottom wall 74e. The junction between the portions 74d and 74e defines a sort of toe 76 (FIGS. 2, 4, 5, 7 and 8) for engaging a support such as is designated at 77 in FIG. 4 of the drawings. The space defined within the portions 74d and 74e of the stand 74 and the housing 31 defines a switch chamber 78, best shown in FIG. 8 of the drawings.

In order to support a switch within switch chamber 78, the wall 74e of the base stand 74 is provided with a circular opening 79, within which opening is reciprocally mounted a flanged outer cup-shaped switch button 80. The flange 80a of button 80 rests on the portion of wall 74e defining opening 79, as clearly shown in FIG. 8 of the drawings. This switch button, however, has a lower central opening for reciprocatingly supporting therein a molded inner switch button 81 having an annular lateral projection 81a resting on the walls defining the lower opening in outer switch button 80. A supporting U-shaped bracket 83 spanning the opening 79 is secured to the wall 74e by fastening means 82. A relatively heavy coiled compression spring 84 is interposed between the bracket 83 and the outer cup-shaped switch button 80, with the lower end of spring 84 disposed in the cup portion of button 80 and, in fact, disposed in an annular recess 86 defined therein.

The bracket 83 also supports a conventional switch generally designated at 88, preferably of the type comprising an insulated switch housing from which projects a threaded mounting support 89 in the form of a hollow tube reciprocably mounting therein a switch actuating plunger 90. Preferably, the switch 88 is of the type that, upon successive actuations of the plunger 90, alternate opening and closing of the switch contacts occurs. Suitable spring means (not shown) normally bias the plunger 90 in a downward direction as viewed in FIG. 8 of the drawings. To accommodate this type of switch, the bracket 83 is provided with a suitable opening for receiving the tubular threaded extension 89 of the insulated switch housing 88, and the switch is then supported by clamping nuts 92 and 93, one disposed on either side of the U-shaped bracket 83 and threadedly mounted on extension 89. The inner switch button 81 is suitably secured to the plunger 90. Consequently, upon repeated actuations of the switch button 81, the switch 88 will be alternately opened or closed. The biasing spring for plunger 90 referred to above, which is conventionally a part of switch 88, is relatively weak compared to the spring 84. The switch 88 may also be actuated by the outer button 80 by virtue of the fact that the inner switch button 81 is provided with an annular projection 81a which limits the maximum downward movement thereof. If a sufficient force is applied to the outer switch button 80 to compress the relatively heavy spring 84, the inner switch button 81 is also moved and, consequently, actuation of the switch 88 occurs.

From the above description it will be understood that the force required to actuate the inner switch button 81 is so small that if it were not for the outer switch button 80 and spring 84 the weight of the vacuum cleaner 30 might actuate it accidentally. The spring 84 exerts a sufficient force to prevent such accidental actuation, and yet permits the operator to actuate the switch when desired from the top of the cleaner.

So that the inlet opening 44 into the base shell 31 may be provided with means to connect the inlet tube coupling

35 thereto, there is provided an inlet unit generally designated by the reference numeral 95 and comprising a die casting or the like. This die casting 95 comprises a rectangular portion 95a which has a curved configuration so as to conform with the outer periphery of the wall 31b of the base shell 31. Extending inwardly from the portion 95a is an integral tubular member 95b which extends through the opening 44 and into the chamber defined within the base shell 31. As will be apparent from the ensuing 10 description, this tubular portion 95b makes connection with the disposable dust bag to be described hereinafter. The tubular portion 95b has a smooth circular passageway therein to make a relatively close fit with the tube coupling 35, but includes in the portion thereof outside of base shell 31 adjacent the outside face of the casting 95 an annular recess 96 whereby locking connection with suitable means on a tube coupling 35 described hereinafter can be made, thereby to lock the tube coupling in a releasable manner to the inlet unit 95. A plurality of fastening means 97 (FIG. 5) extend through the wall 31b of base shell 31 to secure the inlet unit 95 thereto. To insure that no air leakage occurs at the opening 44, a suitable gasket 99 (FIG. 9) is interposed between a shoulder 100 defined on the unit 95 and the exterior surface of wall 31b of the base shell 31 surrounding the opening 44. Another relatively large annular sealing gasket 101 surrounding tubular portion 95b within the base shell 31 provides the desired air seal with the disposable bag to be described hereinafter. As illustrated in the drawings, 20 the unit 95 also includes a cover guide finger 95c (FIGS. 7 and 9) which extends into the chamber defined by the base shell 31 through a suitable opening therein. To prevent the escape of the air through this opening, a suitable sealing gasket 102 is provided, as best shown in FIG. 30 9 of the drawings.

From the above description it will be apparent that all of the openings into the chamber defined by the base shell 31, except the top opening and the opening 46 defined by the raised annular shelf 31d (FIG. 6), are sealed 40 by suitable sealing means. This even applies to the openings for fastening means such as 75 and 97, which preferably are provided with sealing washers to insure an airtight casing or housing. The inlet unit 95 is provided on the exterior surface thereof above the tubular portion 95b with a latching recess 103 (FIG. 9), the purpose of which will become apparent as the following description proceeds.

For the purpose of closing the open top of the chamber defined within the base shell 31, there is provided the cover 32 previously described. This cover is a circular 50 slightly dished member having a diameter of the order of that of the rolled rim 31a. A suitable hinge 106 having leaves 106a and 106b joined by a hinge pin 105 secures the cover 32 to the base shell 31. The leaf 106a is fastened to a flattened portion 32a of the cover 32 by fastening means such as a rivet 107 (FIG. 8) and screw 108 (FIG. 5), while the other leaf 106b is secured by fastening means 109 (FIG. 8) to the wall 31b of the base shell 31 immediately above the opening 45 therein. In accordance with the present invention, the same hinge pin 105 pivotally relating leaves 106a and 106b also pivotally supports a hinged air deflector or baffle 110 having spaced ears 110a. The hinged air deflector 110 is disposed over the exhaust opening 73 aligned with the outlet of exhaust elbow 64. The hinged air deflector is provided with a spring latch 111 which holds the deflector in a closed position overlying opening 73 by engaging the inner wall of support 74, as clearly shown in FIG. 8 of the drawings. In this closed position the exhaust air is deflected downwardly thereby eliminating a concentrated rearward blast from the housing 31. However, when it is decided to use the vacuum cleaner 30 for a blowing operation, the exhaust deflector 110 is tipped out of the way and the tube coupling 35 can then be connected by insertion into the opening 73 and latched to the inside wall 70 75

defining this opening. In order that the hinged deflector cover 110 may readily be released by a finger manipulation, the base stand 74 is preferably provided with a recess 113 (FIGS. 5 and 8) immediately below the lower end of the hinged deflector 110. This recess provides an escape passageway for the deflected air and also permits the finger of the operator to be inserted beneath the lower edge of the hinged deflector 110 for ready release of the latch 111.

From the above description it will be apparent that the base stand 74 by itself will not be a sufficient support to position the vacuum cleaner in the storage position shown in FIG. 4 of the drawings. To this end there is provided on the cover 32 what might be referred to as a top stand member 116 which preferably is a molded plastic member having a pair of projecting legs 116a and 116b which together with the toe 76 provide a sort of tripod support. The top stand 116 performs an additional function in that it encloses the hinge 106 and the means for securing the same to the cover 32 and, in a sense, then improves the appearance. Preferably, the top stand member 116 is secured to the cover 32 by fastening means 117 and 118 (FIGS. 5 and 8). If desired, a suitable escutcheon plate 119 may be provided over the top of a portion of the top stand 116 to improve the appearance. The escutcheon plate 119, as is clearly shown in FIG. 3 of the drawings, has the word "Switch" appended thereto, the significance of which will become apparent from the ensuing description.

From the above description it will be understood that the switch 83 and the control buttons 80 and 81 therefor are mounted more or less directly below the escutcheon plate 119 having the word "Switch" thereon. It will be appreciated that if the housewife places her foot on the escutcheon plate 119, as indicated in FIG. 2 of the drawings, and presses downwardly thereon, this will cause upward movement of the outer button 80, as viewed in FIG. 8, against the compression of relatively heavy spring 84, with the resultant actuation of the switch 83. With this arrangement the switch may be actuated in a very simple manner merely by pushing downwardly with the foot on the escutcheon plate 119. However, when the cleaner is in the storage position shown in FIG. 4 of the drawings, this actuation of the switch cannot be accomplished. It will be appreciated that it is oftentimes desirable to operate the cleaner when in the position shown in FIG. 4 of the drawings, and under these conditions the switch may be actuated merely by depressing the inner button 81 which can readily be manipulated by a single finger manipulation.

In order to prevent the escape of air at the junction between the cover 32 and the base shell 31, there is provided a cover sealing gasket 120 which is both a sealing gasket and a protective resilient bumper. The cross section of this gasket is clearly shown in FIGS. 5, 8 and 9 of the drawings and includes a portion which grips the periphery of the cover 32 so as to remain secured thereto. It also includes a compressible portion engaging the rolled upper edge 31a of the base shell 31 so as to provide a satisfactory air seal. In accordance with the present invention, the gasket 120 has an outside dimension which extends beyond the exterior of the wheels 33 and associated tires 59 and, hence, acts as a bumper to preclude the wheels or other parts of the cleaner from marring furniture or walls that might be engaged by the vacuum cleaner 30.

The cover 32, when in the open position, affords complete access to the interior of the base shell 31. It is desirable, however, to provide means to prevent the cover from being opened too far, and to this end there is provided a flexible strap 122 (FIG. 5) which preferably is a plastic coated spring steel member having one end thereof secured by the fastening means 75, which also secures the base stand 74 to the base shell 31. The other end of the plastic sheathed spring steel strap 122 is se-

cured to the interior of the cover by the fastening means 108 which holds the hinge 106 to the cover 32. Preferably, the end of strap 122 secured to the cover 32 is disposed between two curved surfaces, one defined on a block 124 and the other on a clamp 126 held by the same fastening means 108. With this arrangement the strap is caused to assume the loop shown in FIG. 5 of the drawings when the cover is closed.

In order to carry the vacuum cleaner 30 about and to manipulate the cover 32, there is provided a handle assembly generally designated at 128 which is illustrated in the drawings as a two-part assembly comprising a molded plastic rectangular frame member 128a and a U-shaped metal casting 128b. The bight portion of the U-shaped casting and one end of the rectangular molded member 128a cooperate to define a hand grip portion designated as 129 whereby the user may readily grasp the vacuum cleaner 30 to carry it about. Suitable fastening means such as 130 (FIG. 9) secure the elements 128a and 128b into the unitary handle assembly 128. Moreover, this unitary handle assembly is secured as by fastening means 131 (FIG. 5 of the drawings) to a flattened portion 32b of the cover 32. The handle assembly 128 is so designed relative to the distribution of the mass of the cleaner 30 that when the cleaner is grasped by the hand of the user it tends to tilt away from the body thereby being very simple to manipulate and to carry.

So that the sealing gasket 120 is effective completely to seal the open top of the base shell 31, it will be appreciated that suitable latching means must be employed which will be capable of stressing the resilient portion of the gasket 120 where it contacts the rolled rim 31a. To this end, there is provided an L-shaped latching member 134 pivotally mounted as by a pivot pin 135 to the handle assembly 128. One leg of the L-shaped latch 134, specifically designated by the reference numeral 134a, has a lateral projection 134b receivable within the latching recess 103 provided in the inlet member 95. The other arm 134c of the latching member 134 is effectively a latch release arm which is biased by means of a torsion spring, generally designated as 140, in a clockwise or latching direction as viewed in FIGS. 5 and 9 of the drawings. This clockwise motion is limited as best shown in FIG. 9 of the drawings when the free end of latch release arm 134c engages the handle assembly 128. The spring 140 is preferably a U-shaped spring member, with the bight portion of the U engaging the arm 134c of latching member 134. The center portion of each leg of the U-shaped spring member 134 is wrapped around the pivot pin 135 and the ends of the legs thereof engage the top of the cover 32 beneath the handle assembly 128. With this arrangement the spring 140 normally biases the latching portion 134b of the L-shaped lever 134 into latching engagement with recess 103 when the cover 32 is closed, and in this position sealing gasket 120 is forced into sealing engagement with the rolled rim 31a of base shell 31. If desired, a suitable decorative escutcheon plate, such as 143, may be secured to the arm 134c of latching lever 134. This escutcheon plate preferably will include information such as is shown in FIG. 3, which indicates that the portion 134c of the latching lever 134a should be pushed or pressed to open the latch.

For the purpose of guiding the closing movement of cover 32, there is provided a guide member 145 of somewhat L shape, having one arm of the L secured to the inside cover 32 as by rivets 146 (FIG. 9). Guide member 145 includes a depending rigid portion terminating in bifurcations 145a engageable with guide pin 95c to guide the cover 32 during the final closing movement thereof. Guide member 145 also includes a depending loop 145b to define a shoulder or notch for supporting the disposable bag described hereinafter.

The heart of any vacuum cleaner is, of course, the suction producing means, and an important feature of the present invention is the provision of a powerful motor driving a single-stage turbine type fan so as to pro-

duce a suction capable of lifting a column of water seventy inches in height, which is a substantially greater suction than is available in other vacuum cleaners now on the market. The motor and fan portion of the cleaner and the mounting thereof are best shown in FIGS. 5, 6, 7, 10, 11 and 12 of the drawings. Referring now to the drawings, the motor and fan assembly, generally designated by the reference numeral 150, is suitably supported within the center portion of base shell 31 and specifically upon the annular ledge 31d, as clearly shown in FIG. 10 of the drawings. This motor and fan assembly 150 includes an electric motor 151 comprising a motor housing 152 of cylindrical configuration having spiderlike projections 152a of curvilinear form supporting an integral annular upper bearing support 152b. The motor housing is effectively a bell-shaped member with the portion of the closed end of the bell cut away to define the ribs 152a supporting the annular bearing support 152b. The lower open end of the motor housing 152 is provided with a plurality of laterally extending lugs 152c (FIGS. 6 and 10) which merge into a laterally extending peripheral flange 152d. The peripheral flange 152d, as will become apparent from the ensuing description, is a clamping flange for clamping the motor and fan assembly 150 to the annular ledge 31d.

Secured to the lower end of the motor housing 152 is a bearing support 155 which has a circular configuration conforming to the configuration of the housing 152 including an axially extending flange 155a receivable in close fitting relationship within a cooperating counterbore 156 defined within the lower end of the motor housing 152. The bearing support 155 further includes a laterally extending integral annular flange 155b adapted to be in face-to-face engagement with the flange 152d of the motor housing 152, as is clearly apparent from FIG. 10 of the drawings. Additionally, the bearing support 155 includes integral radially disposed arms 155c for supporting an integral annular lower bearing support 155d disposed in aligned relationship with the upper bearing support 152b. The bearing support 155 further includes a plurality of circumferentially spaced laterally extending lugs 155e substantially identical in shape and spacing with the lugs 152c of the housing 152 and adapted to be aligned therewith so that suitable fastening means such as 158 extending upwardly through the lower lugs 155b and threadedly engaging tapped openings in the upper lugs 152c may secure the bearing support 155 and motor housing 152 in assembled relationship as shown in FIG. 10 of the drawings. Mounted within the lower annular bearing support 155d is a suitable roller bearing 160 held in place by a bearing retainer 161, which in turn is secured by screws 162 threadedly engaging tapped openings in the radial arms 155c. In a device built in accordance with the present invention, the bearing retainer 161 was of triangular shape, and the apices of the triangles had openings for the fastening means 162 and were secured one to each of three arms 155c. The upper bearing support 152b similarly supports therein a suitable roller bearing 164. An expansion ring type bearing retainer 159 retains upper bearing 164 in upper bearing support 152b. Preferably, the top of the annular upper bearing holder 152b is closed by a suitable plastic cap 163, best shown in FIG. 10 of the drawings.

Mounted within the motor housing 152 is a suitable field structure generally designated at 165, including a field winding 165a, which field structure is suitably clamped within the housing 152 by fastening means designated as 166. An armature 167, including an armature shaft 168 and a commutator 169, is journaled in a conventional manner within the bearings 160 and 164. A pair of diametrically opposed brush holders 170, preferably formed of a molded plastic material, are secured to the motor housing as by fastening means 172 extending through integral ear portions 170a. A tubular portion 170b of each brush holder extends toward

the commutator 169 between the spiderlike arms 152a of the motor housing 152. Mounted within each tubular portion 170b (FIG. 10), which is preferably formed of a molded phenolic resin, is a brush holder sleeve 176, a brush 177, and a coiled spring 178 which biases the brush into contacting engagement with the commutator 169. The conventional electrical connections including lead 180 (FIG. 5) are made between the brushes and the motor windings. In an embodiment built in accordance with the present invention, the electric motor 150 was a one and one-half horsepower electric motor, thereby capable of producing a very powerful suction.

Secured to the lower end of the motor shaft 168 is a fan member generally designated at 181, and, as best shown in FIGS. 10, 11 and 12 of the drawings, this fan member comprises a pair of circular metal plates or disks 182 and 183 which are secured together in spaced relationship by curved blades 184. These blades taper in height from the center of the fan 181 toward the periphery thereof. In a fan built in accordance with the present invention, the plates 182 and 183 had a diameter of the order of six inches and the height at the narrowest portion of the curved blades 184 was of the order of one eighth of an inch and the widest portion thereof was of the order of three eighths of an inch. For securing the plates 182 and 183 and the blades 184 together to produce a unitary construction, the blades are provided along both edges at spaced points therealong with rivet-like projections 184a, which projections are adapted to extend through spaced openings 187 and 188 in the plates 182 and 183, respectively, as clearly shown in FIG. 12 of the drawings. The projections 184a, after being inserted in openings 187 and 188, are mutilated as indicated at 189 by a suitable tool so as effectively to rivet the plates 182 and 183 to the curved blades 184, as clearly shown in FIG. 12 of the drawings. The upper plate 182 is provided with a relatively large centrally disposed axial air inlet opening 190. Air enters this axial inlet and is discharged at the periphery of the fan 181.

For the purpose of securing the fan 181 to the motor shaft 168, the lower end of the shaft is threaded as indicated at 168a and the disk 183 is provided with a central opening 192 sufficiently large to receive the shaft 168 therein. An upper spacing and clamping member 193 having a reduced portion 193a receivable within the annular lower bearing support 155d positions the fan 181 relative to the motor shaft 168 and the fan is secured thereto by a lower clamping washer 194 and the nut 195, the latter threadedly engaging the portion 168a of the shaft 168. It will be apparent that the disk 183 is clamped between the upper clamping member 193 and the washer 194.

It will be appreciated that a vacuum cleaner could produce either a high volume of air flow or a high static pressure. In the ordinary cleaning operation the suction nozzle, which may be embodied in the rug cleaning attachment 41 or in any other attachment secured to the wand 39, is substantially closed in that it is in engagement with rugs, upholstered furniture and the like, and it is important to develop a high static pressure. This high static pressure is usually stated in terms of water lift, and, as has been pointed out above, a cleaner built in accordance with the present invention had a water lift of seventy inches. To produce a high static pressure, the common practice has been to increase the number of fan wheels to produce a multistage fan. The air entering an axial inlet near the center of the first stage is discharged peripherally and supplied to the axial inlet of the next adjacent stage. This arrangement increases the static pressure but reduces materially the volume of air. With the present invention a very high volume of air and also a high static pressure are produced.

In order to convert the kinetic energy of motion of a large volume of air to a desirable static pressure, there is provided a diffuser generally designated at 196

which is essentially a disc molded of a phenolic resin or the like preferably secured to the underside of the bearing support 155 by the same fastening means 158 which holds the motor housing 150 and the bearing support 155 in assembled relationship. As illustrated, this diffuser 196 has a central or axial opening 197 aligned with the axial inlet 190 in the fan 181. Preferably a suitable annular gasket 198 provides an airseal around the opening 197 by engaging with the upper surface of the diffuser 196 and with a cooperating grooved annular ring 155f defined on the lower bearing support which ring has an annular gasket confining recess 199 therein. When the fastening means 158 are in the position shown in FIG. 10, the gasket 198 is compressed as indicated so as to move into the recess 199 and an airseal is provided. All the air drawn into the axial inlet 190 of the fan 181 must therefore pass through the motor housing 151 through the openings between the curved spiderlike arms 152a, and, of course, this air stream produces a cooling action on the motor windings which is desirable. Secured to the bottom face of the diffuser 196 is a diffuser cover 200 preferably formed as a metal stamping or the like which is suitably secured to the diffuser as by bolts 201. It will be apparent that the diffuser 196 and the diffuser cover 200 define therebetween a fan chamber 203 for the fan 181. Integrally formed with the diffuser plate on the underside thereof and disposed about an annular area immediately outside the periphery of the fan 181 in the fan chamber 203 are diffusing members 196a which are angularly disposed vanes best shown in FIG. 11 of the drawings. Air discharged from the periphery of the fan 181 strikes these angularly disposed vanes thereby to convert the velocity or kinetic energy of the discharged air to potential or pressure energy or what might be called static pressure. For the purpose of muffling the air escaping from the periphery of the fan chamber 203 between the vanes 196a, there is provided a muffler 205 (FIGS. 5, 10 and 11) which is preferably formed from a strip of foam plastic such as a polyester urethane foam. This strip is arranged in the form of an endless loop and is slipped around the periphery of the chamber defined by the diffuser 196 and the diffuser cover 200 so that all the air discharged from the fan chamber 203 must pass through the muffler 205.

In view of the detailed description with respect to the motor fan unit 150, it will readily be appreciated how this unit is supported within the cleaner housing defined by base shell 31 and the cover 32. As best shown in FIG. 10 of the drawings, the motor fan unit 150 is inserted into opening 46 from the bottom and the rectangular notch 49 permits this insertion even with the brush supports 170 attached to the motor. In order to reduce to a minimum the transmission of any vibration from the motor fan unit 150 to the housing 31, there are provided a pair of annular resilient gaskets 207 and 208, one disposed above and one below the annular shelf. These members 207 and 208 are readily resilient mounting or cushioning means and they are each provided with notched out portions for receiving the lugs 152c on the motor housing 152. The resilient mounting gasket 207 is disposed above the flange 152d and between that flange 152d and the annular motor supporting surface 31d. The other mounting ring 208 is disposed above the annular support 31d. A suitable two-piece annular clamping ring 210 of somewhat L-shaped cross section, comprising sections 210a and 210b (FIGS. 5, 7 and 10) is secured as by fastening means 211 engaging tapped openings in the lugs 152c which openings already receive the fastening means 158 from the lower end thereof. Thus the motor and fan unit 150 is secured within the opening 146 and resiliently clamped to the support 31d in a manner so that vibrations of the motor and fan unit 150 will not be transmitted to the base shell 31.

Although, as will become apparent from the ensuing

description, a disposable dust bag will be employed within base shell 31, it is desirable to provide a permanent dust screen for protecting the motor fan unit 150 should, for any reason, something happen to the disposable dust bag to be described hereinafter. To this end there is provided a cylindrical filter screen 212 having an internal diameter so as to snugly fit about the outside of the raised portion of the base shell 31 defining the annular support or platform 31d as is clearly shown in FIGS. 5, 8 and 10 of the drawings. This permanent filter screen 212 preferably includes a cylinder formed of steel screen wire which has been rayon flocked both on the inside and the outside. In a device built in accordance with the present invention a rayon flocking of the order of .045 of an inch was employed on the inside of the filter screen 212 and a similar flock of the order of .025 of an inch was employed on the outside. This rayon flock was defined as a five denier flock. It is desirable to insure the necessary porosity but at the same time prevent dust particles from reaching the motor should anything occur to the disposable filter bag. The upper part of the filter screen 212 is closed by a filter cover 213 which may be stapled or otherwise secured to the cylindrical filter screen 212. For the purpose of maintaining the filter screen 212 and its associated cover 213 in position, there preferably is provided a Z-shaped bracket 215 (FIGS. 5 and 7) secured as by a screw 216 to one of the arms 152a and the motor housing 152. The filter screen 212 is then held in position by a fastening means 217 extending through an opening in the cover 213 and threadedly engaging Z-shaped bracket 215 as clearly shown in FIG. 5 of the drawings.

In order to supply electric power to the vacuum cleaner 30 of the present invention, there is provided the conventional power cord 220 which terminates in a plug connector 221. Preferably the plug connector 221 is provided with lateral projections 221a defining a cord receiving notch or recess therein whereby when the cord is wrapped in a manner described hereinafter and shown in FIG. 4 of the drawings the plug connector 221 may be clamped to one of the cord turns to maintain the cord in this position. The end of the power cord 220 adjacent the vacuum cleaner 30 preferably terminates in a molded enlargement 222 (FIG. 7) terminating in a pair of lateral flanges (not shown) integrally formed with the insulation of the power cord 220. A strain-relief member 223 is then provided, having recesses for receiving the molded enlargement 222 and its lateral flanges, not shown, which is clamped to the underside 50 of base shell 31 by screws 224 (FIG. 7).

For the purpose of enclosing the fan unit which extends outside the base shell 31 and to direct the air exhausted from the fan unit into the exhaust elbow 64 where it passes through the annular wall portion 31c of base shell 31, there is provided a bottom pan 226. This bottom pan is secured by suitable screws 227 (FIGS. 5 and 8) to flanged tubular members 228 which are welded at spaced points to the bottom of base shell 31, one of which is clearly shown in FIG. 8 of the drawings and two of which are shown in FIG. 5 of the drawings. The bottom pan 226 preferably is provided with a peripheral flange 226a best shown in FIGS. 5, 8 and 9 for engaging with the underside of the annular surface 31c of base shell 31. Preferably the bottom pan 226 is provided with suitable openings through which the electrical conductors from the power cord and the electrical conductors leading to the switch 88 may extend.

The motor fan unit 150 is preferably mounted within the vacuum cleaner 30 in an off center position so that the center of gravity is slightly to the rear of the axis to the wheels 33 or, in other words, is slightly to the side of the center of the cleaner most closely adjacent to the switch 88. Normally, when the vacuum cleaner 30 is in the position shown in FIG. 5 of the drawings, it

is lightly resting on the outer switch button 80. However, in order to provide a resting point should it tip in the other direction, the pan 226 is provided with a depending portion 226b of somewhat conical shape at the apex of which is provided a plastic rivet 230. This rivet is inserted through an opening in the apex and secured by suitable fastening means 231 inside the pan as clearly shown in FIG. 5 of the drawings. This plastic rivet 230 in effect defines a skid of a molded plastic of the same color as the cleaner housing, and it will be apparent that this plastic skid will not mar or scratch as might a metal member, and furthermore no paint will wear off from it as would be the case if it were a metal member since the appropriate color is molded right into the plastic.

The vacuum cleaner 30 described above is capable of employing a disposable bag or waste container and to this end there is provided a disposable paper bag 234 which when expanded is an elongated tubular member closed at both ends. At the center of the bag there is provided a rectangular cardboard stiffener member 235 having an opening therein of a size to receive the inlet extension 95b. There is of course also an opening in the disposable bag aligned with the opening in the cardboard member. In accordance with the present invention, the cardboard member secured to the center of the disposable bag 234 is of such a size that the bottom edge thereof is receivable within the recess 50 in the base shell 31 and it abuts the shoulder defined by the end of the rib 31e at the front center of base shell 31 so as to force the cardboard member 235 against the sealing gasket 101 as clearly shown in FIGS. 5 and 9 of the drawings. The upper end of the cardboard member 235 is receivable within the notch defined in the member 145 by virtue of the loop 145b. With this arrangement, as the cover is closed and as clearly shown in FIGS. 5 and 9 of the drawings, the cardboard 235 is forced into sealing engagement with the gasket 101 so that no air leakage occurs between the inlet tube 95b and the entrance to the disposable bag 234. The elongated tubular disposable bag can then be disposed in the annular chamber defined between the walls 31b of the base shell 31 and the filter screen 212 as is clearly shown in FIG. 7 of the drawings.

Preferably for storage purposes the disposable bags 234 are pleated so that they can be folded into a very small unit. The filter bag 234 is made of a paper having the desired porosity to permit the desired air flow therethrough and at the same time retain therein the dust and dirt collected. It will be apparent that the replacement of a filter bag is a very simple matter, since by opening the cover 32 the housewife has ready access to the filter bag which upon opening the cover releases the upper edge of the cardboard 235 and it is merely necessary for the housewife to slip the cardboard off the end of inlet tube 95b and remove the bag. The steps need merely be reversed to insert a new disposable bag. By virtue of the large diameter, low, flat housing a very large capacity disposable bag can be employed.

Cord storage has always been a problem with vacuum cleaners and the vacuum cleaner 30 is especially adapted to make this problem a simple one. As best shown in FIG. 4 of the drawings, the cover stand 116 and the handle assembly 128 project at diametrically opposed sides from the cover 32 and provide a simple way in which the cord may be supported on the cover. This as there illustrated merely comprises wrapping the cord around the projections of the cover stand 116 and the handle assembly 128. The cord clip 221a then is clamped to an adjacent card turn to hold the cord in this position.

In order to simplify the hose storage problem, there is provided in accordance with the present invention a hose hanger generally designated in FIGS. 1, 13 and 14 by the reference numeral 238. This hose hanger is there illustrated as formed of a molded plastic material including a straplike portion 238a terminating at one

end with a loop 238b and at the other end with an opening 239 into which the loop 238b may be inserted after the strap 238a has been clamped around the hose 36. Interlocking portions designated as 238c and 238d (FIG. 13) are preferably provided on the strap so that once it is looped around the hose it remains locked thereon in a predetermined position therealong and the operator can then take the loop 238b and hook it on any suitable hanger or nail thus providing a very desirable support for the hose. Moreover, the hanger can be positioned at any desired position along the hose.

In view of the powerful suction which is produced by the cleaner of the present invention, there are certain cleaning operations where this suction may be too great, and in accordance with the present invention there has been provided a suction adjusting member 40 which is associated with the curved tube 38 as best shown in FIGS. 1 and 13 of the drawings. As there illustrated, the curved tube is provided with an opening 241 disposed between a pair of rolled spaced ridges 38a and 38b defined in the curved tube 38. The suction control member or bleed ring 40 then comprises a split ring preferably molded of a suitable plastic, which fits into the space between the ridges 38a and 38b and may be rotated to adjust the effectiveness of the opening 241 which may be completely uncovered (as shown in FIG. 13) to get minimum suction or covered to any desired degree (as shown in FIG. 1) to vary the suction. Of course, when opening 241 is completely covered by bleed ring 40, the maximum suction will be obtained at the particular attachment connected to the wand 39. Preferably, a bleed ring stiffener spring (not shown) may be employed to cause the bleed ring to closely embrace the curved tube between the ridges 38a and 38b.

As was mentioned above, the suction hose 36 is preferably a nylon reinforced flexible vinyl hose which is threaded onto a threaded end 37a of the tube portion which with curved tube 38 defines the swivel 37. The other end of hose 36 is threaded onto a threaded end 35a of the coupling 35. Preferably, the junction between the coupling 35 and the hose 36 is covered by a coupling collar 245 which may be cemented in position. A collar 246 preferably also encloses the junction between the hose 36 and the swivel 37. This collar 246 is preferably also cemented to the hose 36. The collars 245 and 246 are preferably formed of a molded plastic of some sort.

In order to secure the coupling 35 into the opening defined by tubular extension 95b of inlet unit 95 or into the outlet opening 73 and to secure the curved tube 38 to the wand sections 39 as well as to secure the wand sections 39 to certain attachments such as the rug cleaning attachment 41, the coupling 35, the curved tube 38 and the wand sections 39 are each provided with identical locking means, the details of which are best shown in FIG. 17 of the drawings, where a part of the wand portion 39 is shown in section. It should be understood that identical arrangements are provided for all tube parts to be locked or secured to another part and the same reference numerals are used for corresponding parts.

Referring now to the portion of tubular wand 39 shown in FIG. 17 of the drawings, there is provided in the walls thereof adjacent the end a pair of spaced openings 247 and 248. A locking member 249 is provided having a latch portion 249a and a finger manipulating knob 249b, all formed as an integral unit. The locking member 249 is associated with the coupling element 35, the curved tube element 38 or the wand element 39 by having the portions 249a and 249b extend through the spaced openings 247 and 248, respectively defined in the associated elements 35, 38 or 39. A suitable leaf spring 250 secured to the associated element 35, 38 or 39 by a rivet 251 resiliently biases the locking elements 249 to the positions shown in FIGS. 1, 13 and 17 of the drawings. A housing member 252, disposed within elements

35, 38 or 39, having one end secured by the rivet 251 and the other end secured by the rivet 253, completely houses the locking member 249 and the leaf spring 250 and provides a smooth passageway within the associated element, whether it be the wand 39, the coupling 35 or the curved tube 38. In FIG. 17 of the drawings the wand 39 is indicated as being locked to a tubular extension 254a of a swivel 254 associated with attachment 41, which tubular extension is provided with a latch opening 255 for receiving the latch portion 249a of locking member 249. To separate the wand 39 from the attachment 41, it is merely necessary to depress knob 249b against the force of leaf spring 250 until latch portion 249a is free of the opening 255, whereupon the wand 39 may be moved out of telescopic engagement with the tubular portion 254a. In the same manner the curved tube 38 may be connected to the wand 39, which is also provided with a latch opening corresponding to latch opening 255 receiving the latch portion 249a of lock member 249 of the curved tube 38 as shown in FIGS. 1 and 13 of the drawings. Similarly, the latch portion 249a of the coupling 35 is receivable in the annular recess 96 of inlet unit 95 or engageable with the inner edge of the exhaust opening 73 defined in base stand 74 thereby insuring that the coupling is locked to the vacuum cleaner until removal therefrom is desired.

Referring now to the rug attachment shown in FIGS. 1, 16 and 17 of the drawings, it comprises a molded plastic housing member 260, which is open on the bottom. Rearwardly directed integral extensions of the housing 260 define a swivel socket portion 260a for receiving therein the swivel 254. Preferably the swivel 254 which may comprise a die casting, and the socket portion 260a are pivotally secured together by a pair of pivot pins 263. The housing 260 and the swivel 254 are provided with aligned openings 264 and 265, respectively, whereby suction applied to the tubular extension 254a of swivel 254 will be effective within housing 260.

In order that the rug attachment 41 will not mar furniture if it should accidentally be engaged by the attachment, a resilient bumper member 266 of U-shaped cross section, as best shown in FIG. 17 of the drawings, encloses a peripheral flange 260b surrounding the downwardly directed opening in housing 260. The ends of this bumper member 266 are preferably wedged in recesses provided therefor toward the rear of housing 260 whereby ready replacement of such bumper member can be accomplished.

Mounted within the housing 260 is a nozzle shoe 267 which preferably comprises a die casting of somewhat similar configuration to the housing 260. The nozzle shoe 267 includes an integral longitudinally extending partition member 267a which divides the nozzle shoe into an elongated narrow nozzle chamber 268 forwardly of the partition 267a and a brush chamber 269 rearwardly of the partition 267a. Both of these chambers 268 and 269 are open at the bottom, but the brush chamber 269 is closed at the top, whereas the nozzle chamber 268 is provided with a top opening 270 leading into the housing 260 and connected to the swivel 254 through the aligned openings 264 and 265. For the purpose of connecting the brush chamber 269 with the nozzle chamber, the partition 267a is provided along its lower edge at least for the length of the opening 270 with a plurality of spaced recesses 272 through which dirt particles released in the brush chamber 269 may enter the nozzle chamber 268. These recesses 272 define between them teethlike members 273 which also act to some extent as a litter rake. To improve the dirt removal, there is provided at the front of the nozzle shoe 267 and extending along the entire length of the nozzle chamber 268 a litter rake 274 preferably formed of a molded rubberlike material and including a plurality of angular extending resilient teethlike members 274a. Any suitable means for securing the litter rake in position may be employed. In an

embodiment built in accordance with the present invention, the litter rake 274 was pressed into a recess provided therefor in the nozzle shoe 267. The housing 260 and the nozzle 267 are held together as a unitary structure by suitable fastening means such as bolts 276 and 277.

To support the rug attachment 41 on the surface to be cleaned, a pair of rear wheels 278 and a pair of front wheels or roller members 279 are provided. The front wheels 279 may be roller members formed of nylon or the like disposed in suitable recesses 280, one at either end of the nozzle shoe 267. Suitable pins 281 driven into aligned openings defined in nozzle shoe 267 rotatably support the rollers or front wheels 279. The rear rollers or wheels 278 are preferably pivotally mounted to a pair of rearwardly directed integral extensions 267b of the nozzle shoe 267. These rearward extensions 267b are disposed one on either side of the socket portion 260a of the housing 260 whereby the wheels or rollers 278 are disposed on either side of the socket 260a and the swivel 254.

In order adjustably to position a brush within brush chamber 269, the nozzle shoe 267 is provided with pairs of spaced guide members, two pairs designated by the reference numerals 267c and 267d being shown in FIG. 16 of the drawings adjacent one end. It will be understood that identical pairs of such guide members will be provided on the other portion of the nozzle shoe 267 not shown in FIG. 16. Also, at the center, a single guide member 267e is provided. These guide members 267c, 267d and 267e position and vertically guide the movement of a brush 284 which has a rectangular support member 284a from which a plurality of tufts or bristles 285 extend. The maximum downward movement of the brush 284 is limited by the pins 281 supporting the rollers 279 as clearly shown in FIG. 16 of the drawings. A suitable leaf spring 287 disposed between the top of support 284a and the top of the brush chamber 269, as viewed in FIG. 17 of the drawings, constantly biases the brush 284 downwardly.

It will be appreciated that for best cleaning action the position of this brush will vary with the types of surfaces cleaned, and to this end there is provided a pivotally mounted brush lock plate 289 preferably secured as by a fastening means 290 within the brush chamber 269. The brush lock plate 289 includes a manipulating projection 289a and a pair of camlike extensions 289b and 289c. The projection 289b defines an inclined surface engageable with the bottom of the brush support 284a as clearly shown in FIGS. 16 and 17 of the drawings, so that, dependent upon the angular position of the brush lock plate 289, the relative vertical position of the brush 284 may be selectively controlled. As best shown in FIG. 16 of the drawings, the nozzle shoe 267 is provided with indicia such as "rugs," "carpets" and "floors" positioned at various angular positions of the brush lock plate 289, and the extension 289a is in effect also an indicator to indicate the particular setting. As shown in FIG. 16, the brush is adjusted for cleaning rugs, which means that the brush is in its most retracted position. The extension 289c forms a stop member engageable with an integral projection 267f to limit the maximum clockwise rotation, as viewed in FIG. 16 of the drawings. This extension 289c, when the attachment is set for cleaning hard surfaced floors, moves above the top of brush support 284a, and in effect eliminates the action of spring 287 and provides a rigid support causing the brush to engage the floor being cleaned. When the brush lock plate 289 is in any other position wherein the extension 289c is not above the support 284a, then the spring 287 resiliently positions the brush so that it may move upwardly if the contacting force with the rug or carpet is sufficiently great.

In view of the detailed description included above, the operation of the suction cleaner of the present invention will be readily understood. It will be appreciated that

when the motor and fan assembly 150 is energized, air is drawn through the inlet opening and passes through the pores in the disposable bag 234 leaving dirt and dust particles inside the bag. The air then passes through the screen filter 212 surrounding the motor unit, which filters out any remaining dust particles which could damage the motor. The air is then drawn through the motor and exhausted at the rear of the unit around the base. The suction can be adjusted by the bleed ring 40 to any desired amount.

While there has been shown and described a particular embodiment of the present invention, it will be apparent to those skilled in the art that various changes and modifications may be made without departing from the invention in its broader aspects, and it is, therefore, contemplated in the appended claims to cover all such changes and modifications as fall within the true spirit and scope of the invention.

What is claimed as new and desired to be secured by Letters Patent of the United States is:

1. In a suction cleaner the combination of a housing, spaced means for supporting said housing, switch means mounted on said housing comprising relatively movable contacts, a switch actuating member projecting from the bottom of said housing and operatively connected to actuate said contacts when moved toward the bottom of said housing, spring means normally biasing said switch actuating member away from the bottom of said housing, motor driven fan means supported by said housing, the center of gravity of said suction cleaner with respect to said spaced means being such as to cause said housing to pivot about the axis of said spaced means until said switch actuating member engages the surface supporting said cleaner, whereby said contacts are actuated by applying a force to the top of said housing directly above said switch actuating member of sufficient magnitude momentarily to compress said spring.

2. A suction cleaner comprising a housing, a pair of wheels supporting said housing from a surface to be cleaned, switch means mounted on said housing comprising relatively movable contacts, a first switch actuating member projecting from the bottom of said housing for actuating said contacts, a second switch actuating member disposed adjacent said first switch actuating member and arranged when moved toward the bottom of said housing to move said first switch actuating member to actuate said contacts, spring means normally biasing said second switch actuating member away from the bottom of said housing, and motor driven fan means supported by said housing, the center of gravity of said suction cleaner with respect to said wheels being such as to cause said housing to pivot about the axis of said wheels until said second switch actuating member engages said surface, said second switch actuating member preventing said first switch actuating member from engaging said surface, said contacts being actuated by applying a force to the top of said housing above said switch actuating members of sufficient magnitude to compress said spring.

3. The suction cleaner of claim 2 wherein said second switch actuating member is cup-shaped and said spring means is a helical compression spring having one end received in said cup-shaped switch actuating member.

4. In a suction cleaner having a pan-shaped housing and a pair of wheels connected to said housing at diametrically opposed portions thereof for supporting said housing from a surface to be cleaned, switch means mounted on said housing comprising relatively movable contacts, a first flanged switch actuating member projecting from the bottom of said housing for actuating said contacts, a second switch actuating member concentrically disposed relative to said first switch actuating member and arranged when moved toward the bottom of said housing to engage the flange on said first switch actuating member and move said first switch actuating member to actuate said contacts, spring means normally biasing said second switch actuating

ing member away from the bottom of said housing, motor driven fan means supported somewhat centrally of said housing, said suction cleaner including said housing and motor driven fan means being so constructed and arranged that the center of gravity thereof is to one side of the pivotal axis of said wheels whereby said housing pivots about said axis until said second switch actuating member engages said surface, said second switch actuating member preventing said first switch actuating member from engaging said surface, and means for actuating said contacts by applying a force to the top of said housing above said switch actuating members of sufficient magnitude to compress said spring means.

5. The suction cleaner of claim 2 wherein said first switch actuating member is accessible through an opening in said second switch actuating member.

6. A suction cleaner comprising a pan-shaped open top housing having a diameter at least twice its depth, a cover hingedly connected to said housing to close the open top thereof, a pair of wheels at diametrically opposed positions on said housing for supporting the housing from a surface to be cleaned, switch means on said housing comprising relatively movable contacts, a first switch actuating member projecting from the bottom of said housing for actuating said contacts, a second switch actuating member concentrically disposed relative to said first switch actuating member and arranged when moved toward the bottom of said housing to move said first switch actuating member to actuate said contacts, spring means normally biasing said second switch actuating member away from the bottom of said housing, motor means disposed within said housing controlled by said switch means, said cleaner including said housing and motor means being so constructed and arranged that the center of gravity of said cleaner is such as to cause said housing to pivot about the axis of said wheels until said second switch actuating member engages said surface, said second switch actuating member preventing said first switch actuating member from engaging said surface, and means for actuating said contacts by applying a force to the top of said housing above said switch actuating means of sufficient magnitude momentarily to compress said spring.

7. A suction cleaner comprising a panlike housing having a diameter several times the depth thereof, a cover hinged to the open top of said housing, a sealing gasket interposed between said cover and said housing, a pair of wheels for supporting said housing disposed at diametrically opposed portions of said housing, electric motor means mounted in said housing, a power cord connected to said motor means and extending from said housing, a carrying handle connected to said cover and projecting from the periphery thereof, a supporting stand projecting from said housing at a point diametrically opposite said handle, said handle and at least a portion of said stand providing a cord support for said power cord.

8. In a vacuum cleaner, the combination of a pan-shaped open top casing having an inlet and an exhaust opening therein, a suction creating fan and motor unit for producing a flow of air through said casing, a cover for said open top, a hinge including a hinge pin for securing said cover to said casing, a dust bag in said casing in the path of said air flow for separating entrained dirt from said air, and an air deflector pivotally connected to said casing by said hinge pin and movable over said exhaust opening to minimize the concentrated air blast which occurs at said exhaust opening.

9. The vacuum cleaner of claim 8 wherein said air deflector includes releasable latch means to hold it over said exhaust opening.

10. A suction cleaner comprising a panlike housing, a cover hinged to the open top of said housing, a sealing gasket interposed between said cover and said housing, means for supporting said housing from a surface to be cleaned, a suction creating fan and motor unit supported by said housing with the motor of said unit comprising

an electric motor disposed centrally of said housing and extending upwardly toward the top of said housing thereby to define an annular chamber within said housing surrounding said motor, the fan of said unit comprising an axial inlet centrifugal single-stage blower disposed below said housing but drivingly connected to said motor, a fan chamber defined in part by the bottom of said housing and enclosing said fan, and stationary diffuser means in said fan chamber for converting the kinetic energy of motion of the air moved by said fan to static pressure, said air being discharged from said fan chamber through peripheral openings in said diffuser means, and an annular muffler means closely embracing the periphery of said diffuser so that air discharged from said openings moves directly through said muffler, the air discharged from said fan chamber passing through said muffler regardless of whether said cleaner is used as a suction cleaner or as a blower.

11. The suction cleaner of claim 10 wherein said muffler comprises a foam plastic.

12. A suction cleaner comprising a housing, a pair of wheels supporting said housing from a surface to be cleaned, switch means mounted on said housing comprising relatively movable contacts, a first switch actuating member projecting from the bottom of said housing for actuating said contacts, a second switch actuating member concentrically disposed relative to said first switch actuating member and arranged when moved in a direction away from said surface to move said first switch actuating member to actuate said contacts, spring means normally biasing said second switch actuating member in a direction toward the surface being cleaned, motor driven fan means supported by said housing, the center of gravity of said suction cleaner with respect to said wheels being such as to cause said housing to pivot about the axis of said wheels until said second switch actuating member engages said surface, said second switch actuating member preventing said first switch actuating member from engaging said surface, and means for actuating said contacts by applying a force to the top of said housing above said switch actuating members of sufficient magnitude to compress said spring.

13. The suction cleaner of claim 2 wherein the force to actuate said second switch actuating member is many times that required to actuate said first switch actuating member.

14. In a suction cleaner having a pan-shaped housing and a pair of wheels connected to said housing at diametrically opposed portions thereof for supporting said housing from a surface to be cleaned, switch means mounted on said housing comprising relatively movable contacts, a first flanged switch actuating member project-

ing from the bottom of said housing for actuating said contacts, a second switch actuating member concentrically disposed relative to said first switch actuating member and arranged when moved toward the bottom of said housing to engage the flange on said first switch actuating member and move said first switch actuating member to actuate said contacts, means normally biasing said first switch actuating member away from the bottom of said housing, spring means normally biasing said second switch actuating member away from the bottom of said housing, said spring means having a force many times that of said means normally biasing said first switch actuating means, motor driven fan means supported somewhat centrally of said housing, said suction cleaner including said housing, and motor driven fan being so constructed and arranged that the center of gravity thereof is to one side of the pivotal axis of said wheels whereby said housing pivots about said axis until said second switch actuating member engages said surface, said second switch actuating member preventing said first switch actuating member from engaging said surface, said contacts being actuated by applying a force to the top of said housing above said switch actuating members of sufficient magnitude to compress said spring means.
